US00D758431S

(12) United States Design Patent
Kim et al.

(10) Patent No.: US D758,431 S
(45) Date of Patent:  Jun. 7, 2016

(54) DISPLAY SCREEN OR PORTION THEREOF
WITH ICON

(71) Applicant: Samsung Electronics Co., Ltd.,
Suwon-si (KR)

(72) Inventors: Jae Jeong Kim, Seoul (KR); So Young Yun, Seoul (KR); Sae Mi Kim, Seoul (KR); Ji Yoon Yoon, Seoul (KR)

(73) Assignee: Samsung Electronics Co., Ltd.,
Suwon-si (KR)

() Term: 14 Years

(21) Appl. No.: 29/494,847

(22) Filed: Jun. 25, 2014

(30) Foreign Application Priority Data

Dec. 27, 2013 (KR) 30-2013-0065722

(51) LOC (10) Cl. 14-04

(52) U.S. Cl.

USPC D14/489

(58) Field of Classification Search

USPC D14/485-495

CPC G06F 3/04817

See application file for complete search history.

(57) CLAIM

We claim the ornamental design for a display screen or portion thereof with icon, as shown and described.

DESCRIPTION

The sole FIGURE is a front view of a display screen or portion thereof with icon showing our new design.

The broken lines illustrate the display screen or portion thereof and form no part of the claimed design.

1 Claim, 1 Drawing Sheet
